United States Patent Office.

HENRY BERGER, OF NEW YORK, N. Y.

Design No. 3,095, dated July 14, 1868.

DESIGN FOR A CENTRE-PIECE.

The Schedule referred to in these Letters Patent and making part of the same.

TO ALL WHOM IT MAY CONCERN:

Be it known that I, HENRY BERGER, of the city, county, and State of New York, have invented a new and original Design for Centre-Pieces; and I do hereby declare the following to be a full, clear, and exact description thereof, which will enable those skilled in the art to make and use the same, reference being had to the accompanying drawing, forming part of this specification.

The drawing, consisting in only one figure, represents my new design for centre-pieces.

This design consists of an oval frame, A, ornamented by a band wound spirally round an oval ring. The frame A encloses an arabesque, B, of corresponding shape, and is surrounded by a series of escutcheons, C, with intervening balusters, D.

What I claim as new, and desire to secure by Letters Patent, is—

The design for a centre-piece, as described and shown.

HENRY BERGER.
